HARNESS MECHANISM FOR LOOMS

Application filed September 12, 1930. Serial No. 481,399.

This invention relates to harness mechanism for looms, and more particularly to the connections between the harness frames and cam levers for shifting the frames.

It has been common practice heretofore to employ leather straps as the flexible connections between the harness frames and cam levers, and to provide hooked wires adapted to be engaged with different holes in the straps to vary the effective length of the straps. Flexible connections formed of cording have also been employed heretofore between the harness frames and cam levers, and while these prior constructions work more or less satisfactorily they tend to stretch while in use and need to be adjusted from time to time.

The present invention therefore contemplates a stronger and more durable form of flexible connection between the harness frames and cam levers, and improved means for adjusting the effective length and tension of the flexible connections.

One important feature of the present invention resides in a construction in which a sheave is secured to the cam lever to be shifted thereby, and has a flexible connection looped about this sheave and the ends of the connection secured to laterally spaced portions of the harness frame, the arrangement being such that the frame can be readily tilted or shifted to the desired horizontal position and then positively maintained in such position by clamping the looped strands of the flexible connection adjacent the sheave.

Another feature of the present invention resides in a harness mechanism employing small, strong and highly flexible cables as the flexible connections between the harness frame and cam lever, and in turnbuckles associated with said cables to facilitate the vertical adjustment of each harness frame and the tension of the cables. Still a further feature of the present invention resides in improved means for attaching the ends of the cable to the harness frame.

The various features of the invention and novel combination of parts will be further understood from the following description

when read in connection with the accompanying drawings, wherein:

Fig. 1 is a vertical sectional view of a loom taken at the rear of the lay to show the harness mechanism of the present invention;

Fig. 2 is a fragmentary side elevation of the loom of Fig. 1;

Fig. 3 on an enlarged scale is a sectional view through a part of the harness frame to which an end of a cable is connected; and

Fig. 4 is an enlarged perspective view of means for adjustably connecting a cable to the cam lever.

The harness mechanism of the present invention may be used upon practically any type of loom designed to employ cam mechanism to shift the harness frames. The accompanying drawings illustrate only the portions of the loom with which the harness mechanism is associated.

The loom illustrated may have the usual supporting structure consisting of the side frames 1, 2 and 3 connected by the beams 4 and the loom is shown in Fig. 2 as having the usual lay 5 supported by the lay swords 6 and rock shaft 7. The lay is rocked towards and from the front of the loom by the crank shaft 8 (see Fig. 2) which is shown as driven by the motor 9 having a pinion 10 that drives the gear 11 secured to the crank shaft. Below the crank shaft 8 is provided the usual bottom shaft 12 which is driven from the crank shaft by the cooperating gears 13 and 14. The parts so far described may have any well-known or preferred construction.

The harness mechanism of the present invention may be employed to operate any desired number of harness frames, since the operating mechanism for each frame is complete in itself and operates independently of the other frames. Four harness frames 15 are employed in the loom illustrated, but since the same type of connection is employed between each frame 15 and its operating cam lever 16 the description of the connections for one frame will be sufficient.

The cam levers 16, one for each harness frame, are pivotally mounted at 17 and are operated by the cams 18 mounted upon the

bottom shaft 12, and each lever 16 is provided intermediate its ends with a roller adapted to engage a cam groove in the cam for operating that lever. The levers 16 are of different length, as shown, to accommodate the distance of the harness frames from the fell of the cloth.

In accordance with the present invention, each harness frame 15 is supported by the flexible strands 19 and 20 provided by looping a flexible element, such as a small cable, about a grooved sheave 21 of a pulley 22. This pulley is connected by any suitable means, such as a link 23, to the proper cam lever 16. The link 23 may have the U-shaped construction best shown in Fig. 4 and has eyes 24 at its lower end adapted to receive the pin 25 that pivotally secures the link to the cam lever.

A turn-buckle 26 is preferably provided between each pulley 22 and link 23 and after a turn-buckle has been rotated to the desired position it may be locked in this position by a spring holder 27 which may have an eye at its upper end for securing the same to the pulley 23 and a laterally extending portion 28 at its lower end adapted to enter a hole in the turn-buckle.

The looped strands 19 and 20 extend upwardly from a pulley 22 about the grooved roller 29 supported by the brackets 30 and then horizontally over the harness frame. One of these strands extends downwardly about a grooved roller 31 and is secured to the upper portion of the harness frame 15 near one side thereof, while the other strand extends downwardly about a second grooved roller 32 and is secured to the upper portion of the harness frame near the opposite side thereof, as will be apparent from Fig. 1.

The heddle frames 15 are preferably formed of light skeleton steel and in the construction shown the ends of the strands 19 and 20 are secured to the frame 15 by providing the upper horizontal bar of the frame with a slot 33 through which the grooved C-shaped sleeve 34 is inserted, and at each side of this apertured bar is provided a rounded strip 35 which may be secured in place by the rivet 36. In this manner a cylinder-like portion is formed to fit the inner curved surface of the C-shaped sleeve 34 as will be apparent from Fig. 3. The end portion of each cable is looped about a grooved sleeve 34 and may then be firmly secured about the same by a clamp 37 having the portions shown adapted to be secured against the opposite sides of the cable by a clamping screw 38. The portions of the clamp 37 may be held in alignment with each other by a pin 39 that is rigidly mounted in one portion and slidably received in the other portion.

In the construction shown, each harness frame 15 is pulled downwardly by the flex-

ible strands 40 and 41 provided by looping a cable or other flexible element about the sheave of a lower pulley 42 connected by a turn-buckle 43 and link 44 to the proper cam lever 16. The cable operating means connected to the upper and lower sides of a harness frame are shown as similar in construction, and the lower strands pass about the lower grooved rollers 45, 46 and 47, and upwardly toward the lever 16. The links 23 and 44 may be provided with the clamps 48 for preventing the legs of the links from springing outwardly out of engagement with the pivot pins 25.

The operating connections forming the strands 19, 20 and 40, 41 are preferably formed of special aeroplane cables that are exceptionally strong and flexible, with the result that the harness frames may be easily raised and lowered by the levers 16 even when the cables are held quite taut.

As a result of the construction of the present invention in which the cables are looped about the sheaves of the pulleys 22 and 42, the harness frames 15 may be easily shifted into the desired horizontal position by pressing down on one side of a frame and up on the opposite side, and after the desired adjustment is secured the looped cables are preferably clamped in this position by applying the clamps 37 to the cables adjacent each sheave as best shown in Fig. 4.

Since the operating connections for each harness frame 15 include an upper turn-buckle 26 and a lower turn-buckle 43, a frame 15 may be raised or lowered relative to its operating lever 16 by taking up one turn-buckle and backing off the other, and each turn-buckle may be rotated to secure the desired tension upon the operating cables.

As a result of the present invention the harness frames may be readily adjusted with a high degree of accuracy to secure the desired manipulation of the shed, and the entire construction while relatively inexpensive to manufacture is strong and durable and operates in a highly satisfactory manner.

What is claimed is:—

1. In a harness mechanism for looms, a harness frame, power operated means for shifting the frame, including a rocking lever, a sheave connected to the lever to be shifted thereby, a cable looped about said sheave and having its ends extending from the sheave connected to laterally spaced portions of the harness frame, a clamp for securing the looped portions of the cable together and rollers for supporting the two strands of the looped cable between their ends and the sheave and arranged so that upon loosening the clamp the frame can be tilted by shifting the cable about the sheave and then held from tilting by setting up the clamp.

2. In a harness mechanism for looms, a harness frame, power operated means for

shifting the frame, including an actuator adapted to be shifted from a going part of the loom, a sheave connected to the actuator to be shifted thereby, a flexible strand looped about said sheave and having its ends connected to laterally spaced portions of the harness frame, rollers for supporting the portions of the strand extending from the sheave to said frame and arranged so that the frame can be tilted by shifting the strand about the sheave and a clamp embracing the two runs of the strand to prevent the frame from tilting after it has been adjusted.

3. In a harness mechanism for looms, a harness frame, power operated means for shifting the frame, including an actuator adapted to be shifted from a going part of the loom, a sheave connected to the actuator to be shifted thereby, a flexible strand looped about said sheave and having its ends connected to the harness frame, rollers for supporting the portions of the strand extending from the sheave to said frame and arranged so that the frame can be tilted by shifting the strand about the sheave, and means for clamping the looped portions of the strand adjacent said sheave to prevent the harness frame from tilting.

4. In a harness mechanism for looms, a harness frame, power operated means for shifting the frame, including a power actuated lever, flexible connections extending between the lever and laterally spaced portions of the top of the harness frame and also between the lever and laterally spaced portions of the bottom of the harness frames, rollers for supporting intermediate portions of said flexible connections, clamping means for the flexible connections to permit the harness frame to be tilted when the clamping means is released and prevent the harness from being tilted when the clamping means is set up, and a turn-buckle between the lever and upper flexible connections and a second turn-buckle between the lever and lower flexible connections and adjustable to vary the tension of said connections and the vertical movement of the harness frame.

5. In a harness mechanism for looms, a harness frame, power operated means for shifting the frame, including a rocking lever, an upper and a lower sheave connected to the lever to be shifted thereby, a cable looped about the upper sheave and having its ends connected to laterally spaced portions at the top of the harness frame, a second cable looped about the lower sheave and having its ends connected to laterally spaced portions at the bottom of the harness frame, rollers for supporting the cables between the frame and sheaves and arranged so that the frame can be tilted by shifting the cables about the sheaves and clamping means for the flexible connections to prevent the frame from tilting after it has been positioned.

6. In a harness mechanism for looms, a harness frame, power operated means for shifting the frame, including a rocking lever, an upper and a lower sheave connected to the lever to be shifted thereby, a cable looped about the upper sheave and having its ends connected to laterally spaced portions at the top of the harness frame, a second cable looped about the lower sheave and having its ends connected to laterally spaced portions at the bottom of the harness frame, rollers for supporting the cables between the frame and sheaves and arranged so that the frame can be tilted by shifting the cables about the sheaves, and a clamp upon the looped portion of each cable adjacent its sheave to hold the harness frame from tilting.

7. In a harness mechanism for looms, a harness frame, power operated means for shifting the frame, including an actuator adapted to be shifted from a going part of the loom, flexible connections between said actuator and harness frame, means for securing the flexible connections to the harness frame including a grooved C-shaped sleeve encircling a part of said frame and having a flexible connection looped about the C-shaped sleeve to lie in its groove, and a clamp for securing the looped portions of the flexible connection about said sleeve.

8. In a harness mechanism for looms, a harness frame, power operated means for shifting the frame, including an actuator adapted to be shifted from a going part of the loom, a cable connection between said actuator and harness, and means for attaching an end portion of the cable to the harness frame including a grooved C-shaped sleeve encircling a part of said frame and having an end portion of said cable looped about the sleeve to lie in its groove.

In testimony whereof, I have signed my name to this specification.

EDWIN W. STONE.
